UNITED STATES PATENT OFFICE.

AUGUSTUS M. FENNER, OF LINESVILLE, PENNSYLVANIA.

TREADLE MOVEMENT.

SPECIFICATION forming part of Letters Patent No. 439,727, dated November 4, 1890.

Application filed February 28, 1890. Serial No. 342,090. (No model.)

To all whom it may concern:

Be it known that I, AUGUSTUS M. FENNER, a citizen of the United States, residing at Linesville, in the county of Crawford and State of Pennsylvania, have invented certain new and useful Improvements in Treadle Movements; and I do hereby declare that the following is a full, clear, and exact description of the same, reference being had to the annexed drawings, making a part of this specification, and to the letters of reference marked thereon.

This invention relates to certain new and useful improvements in treadle movements, and is designed more especially as an improvement upon the device shown, described, and claimed in my patent, No. 363,289, dated May 17, 1887.

It has for its object to simplify and cheapen the construction without detracting from the satisfactory result obtained. I change the form of the lever, dispense with the slot at the upper end thereof, change the form of the pitman, and connect up the parts differently.

Other objects and advantages of the invention will hereinafter appear, and the novel features thereof will be specifically pointed out in the appended claims.

The novelty resides in the peculiar combinations and the construction, arrangement, and adaptation of parts, all as more fully hereinafter described, shown in the drawings, and then particularly set forth in the claims.

The invention is clearly illustrated in the accompanying drawings, which, with the letters of reference marked thereon, form a part of this specification, and in which—

Figure 1 is a side elevation of a machine-frame and crank-wheel with my improved treadle movement applied thereto. Fig. 2 is a front elevation of the same.

Like letters of reference indicate like parts in both views.

Referring now to the details of the drawings by letter, A designates a portion of a machine-frame, and B a crank-shaft sup-

ported in suitable bearings thereon and carrying the drive-wheel C.

50

D is a lever fulcrumed at a on a stud on the frame or otherwise, and at its lower end connected with one end of the stud b, projecting laterally from the treadle E, which has a journal at one end in the frame, as 55 shown best in Fig. 2, and is provided at its rear corner with an angularly-extending stud or lug c, to which the lower end of the pitman F is pivotally connected. The upper end of the pitman is suitably connected with the 60 crank-arm G on the crank-shaft, and at a point above its longitudinal center is formed with a lateral extension d, to which is pivotally connected one end of the horizontal connecting-rod H, the other end of which is 65 pivotally connected with the upper end of the lever D. This lateral extension is preferably integral with the pitman, and is for the purpose of allowing the use of a longer connecting-rod to avoid unsteady jerking 70 motion to the treadle.

What I claim as new is—

1. The combination, with a drive-wheel and its crank-shaft, of the pitman formed with a lateral extension d between its ends, the lever, the treadle, and the horizontal connecting-rod connecting the upper end of the lever with the extension of the pitman, substantially as specified.

75

2. The combination, with the drive-wheel and its crank-shaft, of the treadle having at one corner an angularly-extending lug, the pitman connected at its lower end with said lug and at its upper end with the crank of the crank-shaft and formed between its ends with 85 a rearward lateral extension d, the lever fulcrumed between its ends and connected with the treadle, and the connecting-rod connecting the upper end of the lever with the extension of the pitman, substantially as specified.

80

3. The combination, with the drive-wheel and its crank-shaft, of the treadle having angular extension at one corner, the pitman connected at one end directly with said extension and at the other end directly to the

95

crank of the crank-shaft and formed between its ends with horizontal integral rearward lateral extension, the lever fulcrumed between its ends, connected at its lower end 5 directly to the treadle, and the horizontal connecting-rod connected at one end directly to the upper end of the lever and at the other end directly to the lateral extension of the pitman, substantially as specified.

In testimony that I claim the above I have to hereunto subscribed my name in the presence of two witnesses.

AUGUSTUS M. FENNER.
